FIG. 3.

FIG. 4.

FIG. 5.

Inventor

Harold W. Head

By Norman T. Whitaker
his Attorney

UNITED STATES PATENT OFFICE.

HAROLD W. HEAD, OF ROYAL OAK, MICHIGAN.

ELECTRIC HEATING ELEMENT.

Application filed July 14, 1925. Serial No. 43,478.

An object of my invention is to provide an electrical heating element in which the resistance coil will not sag or in event of breakage will not cause a short circuit.

5 Another object of the invention is to suitably arrange a column of porcelain insulators to permit flexibility and at the same time securely house the heating element.

10 Another object seeks to provide a flexible heating unit which may be easily withdrawn — furthermore my construction permits easy assembling and disassembling and ready replacement of broken or worn parts.

15 A still further object is to provide means for holding the resistance element so that it is at no time enclosed thereby preventing a loss of heat and, at the same time, prolong the eventual burning out of the element.

20 With the preceding and other objects and advantages in mind the invention consists in the novel combination of elements, constructions and arrangement of parts to be herein-after enlarged upon, claimed and illustrated in the accompanying drawing, wherein:

25 Figure 1 is a longitudinal sectional view—partly in section—of the heating unit.

Figure 2 is a horizontal sectional view on line 2—2 of Fig. 1.

30 Figure 3 is a similar horizontal sectional view on line 3—3 of Fig. 1.

Figure 4 is a perspective view of one of the insulating disks, and

35 Figure 5 is a longitudinal sectional view of a standard water heater showing a heating element installed therein.

Similar parts are referred to by the same reference characters throughout the several views.

40 A cylindrical tube 6, preferably of copper, has a closed end 7 and an open end provided with a flange 8 adapted to rest on a shoulder 9 of an internally threaded socket 10 in a casting 11.

45 The flange 8 is held in water-tight engagement with a shoulder 9 by means of a screw threaded ring 12 inserted in socket 10.

An extension 13 is provided on casting 11 by means of which it may be attached to any standard radiator or water heater. The heating element designated in its entirety as 14 is 50 inserted into the copper tube 6. The element comprises a number of porcelain disks 15 formed into a column and a resistance coil 16 inserted on the disks 15.

55 Terminals 17 of the coil 16 are connected to binding posts 18 attached to and insulated

from a journal box 19 which is attached to casting 11 by screws 20. A cable C from a source of electrical energy is attached to binding posts 18 supplying electrical current to 60 the resistance coil 16.

One of the insulating disks, preferably made of porcelain or other ceramic material, is shown in detail in Fig. 4. Around the wall, periphery or circumference of each disk 15 65 are a number of equidistant recesses or cut away portions 21 opening at 22. The insulating walls 23 between adjacent recesses has a flat face or wall 24 and a curved-in convex wall 25.

70 In assembling the disks to form a column adjoining or adjacent disks are reversed as shown in Fig. 3. This novel method of "staggering" the recesses in the disks permits however a continuous aperture or slot through 75 which the resistance coiled wire is passed.

This construction prevents the coil 16 from being entirely enclosed as will be seen in Fig. 1 and permits the heat to more quickly dissipate.

80 At the top and bottom of the column of disks 15 is a porcelain disk 26 having a plurality of apertures 27 which correspond in position with the slots 21. These apertures are connected on the face of the disk by an 85 annular ring 28 as shown in Fig. 2.

Each disk 15 has on its top and base a lug 29 and recess 30 to lock in position and prevent rotation as is clearly shown.

Fig. 5 shows a common water tank heating 90 boiler or tank 31 provided with a cold-water inlet pipe 32 and a hot-water outlet pipe 33 and the heating element which is surrounded by copper tube 6.

The reversing of the insulating disks 15 95 prevents the wire from sagging whereby the wire might touch the copper tube 6. Should the wire break it cannot touch the copper tube preventing a charged radiator which might cause a fire. In effect my construction makes 100 a foolproof and safety device.

Various types of end disks could be used. It should be clearly seen that no portion of the resistance coiled wire is covered. On the contrary the wire is quite exposed. On this 105 feature I wish to lay special stress.

Should the tank 31 shown in Fig. 5 be located in an inaccessible place the object of making my column flexible will be seen. The entire heating element is removed from the 110 top of the tank and can be bent while being removed.

It must be understood that only a preferred embodiment of my invention is herein shown and described and that any departure from it, such as in shape, size or arrangement of parts, may be resorted to without departing from the spirit or the scope of the subjoined claims.

Having thus described my invention, what I claim is:

10. 1. An electrical heating element comprising an insulating body formed of a plurality of separable sections, means on each section to engage an adjacent section and prevent relative rotation of said sections and a plurality of resistance coils within said body forming the sole connection between said sections to yieldingly connect said sections.
20. 2. An electrical heating element comprising an insulating body formed of a plurality of separate sections, means on each section to engage an adjacent section and prevent relative rotation of said sections, and laterally and longitudinally yieldable electrical resistance means passing longitudinally through said sections for holding said sections assembled.
30. 3. An electrical heating element comprising an insulating body formed of a plurality of disks having a plurality of peripheral longitudinal grooves, the grooves in one disk

being aligned longitudinally with the groove of adjacent disks, and resistance coils in said grooves extending from end to end of the body parallel with the axis of the body and forming the sole means for holding said disks assembled.

4. An electrical heating element comprising an insulating body formed of a plurality of separate disks provided with a plurality of grooves extending inwardly from the peripheral surface of the disks, at an angle to planes radial of said disks, a series of resistance coils extending longitudinally of said body parallel with the axis thereof in said grooves and yieldingly connecting said disks and holding the same in longitudinal alignment.

5. An electrical heating element comprising an insulating body formed of a plurality of disks formed with peripheral longitudinal grooves and end disks formed with holes to align with the ends of said grooves, and a series of resistance coils in said grooves and united at their ends through said holes in the end disks, said coils being under tension to yieldingly hold the several disks in assembled relation and in alignment, and means on said disks to prevent relative rotation thereof.

HAROLD W. HEAD.
